UNITED STATES PATENT OFFICE

JOSEPH A. MARTOCELLO, OF PHILADELPHIA, PENNSYLVANIA

ICE-MAKING SYSTEM AND METHOD OF OBTAINING DRY AIR

Application filed November 14, 1923. Serial No. 674,748.

My invention relates to air systems for ice plants and specifically to an arrangement for obtaining an air supply initially cool and low in moisture content and to means for supporting and automatically centering the air inlet tubes within the ice cans.

One purpose of my invention is to use the same air over and over, and to draw the air supply from beneath the cover of the freezing floor to obtain a supply already cold and low in moisture content, reducing further dehydration required and bringing this further dehydration within the range of a brine spray dehydrator without undue dilution of the brine.

Another purpose is to make the air-inlet drop tubes automatically hang vertically, irrespective of variation in the angular placement of the supporting bracket, and preferably at the same time to provide a strong but loose joint connection between the tube and its bracket so that in operation they may be handled as a unit.

A further purpose is to loosely lock the tube to its bracket by means of shoulders above and below the bracket, and to provide ball suspension between the top of the bracket and the bottom of the upper shoulder.

A further purpose is to provide a bracket that will receive and mate with and be properly positioned by the stiffening bead down the center line of commercial cans.

Further purposes will appear in the specification and in the claims.

My invention relates to the processes involved as well as to the mechanism shown for carrying out the process.

Figure 1 is a perspective view showing the parts of a raw water ice system in position.

Figure 2 is a fragmentary enlarged detail from Figure 1.

Figure 3 is a vertical section through an ice can equipped with a portion of my invention.

Figure 4 is a broken sectional detail of Figure 3 to enlarged scale.

Figure 5 is a section of Figure 4 taken along the line 5—5.

Figure 6 is a side elevation of a detail.

Figure 7 is a broken sectional detail from Figure 4.

Figure 7a is a section corresponding to Figure 7 of a modified form.

Figure 8 is a broken bottom plan illustrating the end of the bracket adjacent the can.

Figures 9, 10 and 11 show in section modified forms of a detail.

In the drawings similar numerals indicate like parts.

Describing in illustration and not in limitation and referring to the drawings:—

In the manufacture of raw water ice the use of brine spray dehydrators is common but either special provision has had to be made for reducing the moisture content of the air before it reaches the dehydrator such as very high compression and water cooling, or the relatively high moisture content of the air has resulted in undue dilution of the brine, which brine had subsequently to be concentrated. I have aimed to avoid both of these evils by using the air over and over again, withdrawing it from the freezing tank at the low temperature and corresponding low moisture content of the air in the tank. This air can be passed directly to a brine spray condenser without undue dilution of the brine.

Since the intake air for the previous systems has varied greatly in humidity, due in part to changes in temperature, winter and summer, the initial moisture content has correspondingly varied, even day by day. By my method and apparatus I avoid these variations in moisture content and in temperature of the intake air and am able to predetermine much more accurately the performance of my air supply and to maintain it under much more nearly uniform operating conditions at all times than would otherwise be the case.

By merely properly locating the intake of my air supply I am enabled to obtain the same net result with respect to cooling and moisture as has hitherto been accomplished by a compressor and water-cooling of the high pressure air pipes.

A layout embodying my invention is shown

in Figure 1, showing somewhat diagrammatically a usual freezing floor 15, having covers 16 broken away to show a portion of the freezing tank, including ice cans 17. I show inlet and outlet ammonia pipes 18 and 19 respectively, motor 20 for brine circulation, recording thermometer 21 to record brine temperature, and mercury gauge 22 for testing air pressures.

10 The raw water used may initially not be filtered. During freezing the impurities concentrate in a "core" of water at the center of the can and this water "core" being high in impurities is in best practice pumped out by the suction pump and thrown away, the water pumped out being replaced by fresh water or water that has been filtered. The core suction unit comprises pump 23, operated by motor 24, suction pipe 25, suction hose 26 and discharge pipe 27.

15 20 Fresh raw water from the pipe 28 when used to refill cores passes through the filters 29 and piping 30 and 31 to an intercooler 32, and thence through piping 33 to the supply line 34 having suitable branch connections 35 provided with feed hose 36.

25 30 The air system comprises an air inlet pipe 37 terminating in inlet branches 38 extending into the freezing tank between the brine surface and the freezing floor. A motor-driven pump 39 is thus supplied with intake air from the tank and discharges through pipe 40 to a brine spray dehydrator 41 of any suitable type. One type of this is shown 35 in my application for patent for system of dehydration filed herewith, Serial No. 674,749, and is illustrated, though not with the same completeness, in the present application. The brine for the spray is driven by pump 42 and enters at 43. The air enters at 44 and may be by-passed at 45 through valve 46. Wherever shown 46 represents a hand valve.

40 45 The air comes out at 47 through a separator 48, if desired, passing to the header 49 and thence to the laterals 50.

50 The laterals are fed from the header and supply air to cans 17 through taps 51, flexible connections 52, nozzle terminals 53 and air tubes 54 separate from the cans and suspended in them.

55 I have found it advantageous to have each tube a unit with its bracket, as this reduces the number of parts to be handled when manufacturing ice. It is also desirable for the tube to hang vertically and substantially at the center of the can which is the region last to freeze. In my invention I make the tube and its bracket a unit with a strong but loose connection between the tube and bracket, adapting the unit to rough handling and the tube to always hang vertically, irrespective of slight misplacement of the bracket. I also make the unit very easy to properly place centrally upon the side of the can by having

it mate with the stiffening bead of the can.

The can is shown conventionally. Its upper edge is extended by a rim 55 to rest on sills 56 which may form part of a basket structure. The stiffening bead 57 down the middle of each side of the can is made use of to quickly position the unit, the bracket 58 being grooved at 59 to receive and pass the bead. To properly position the bracket all that is required of an operator is to place the groove 75 over the bead.

The bracket is provided with a passage which may be in the form of a bore 60 over the center of the can to loosely pass the tube 54. The ferrule thimble 61 screwed to the upper end of the tube, forms a support for the tube and is provided with a ball end bearing portion 62. The bore 60 secures the best results in the form of an upward conical flare 63 to receive the ball, as in Figures 4, 85 7, 9, 10 and 11 or terminating in a sharp upper edge 63' to engage the ball as in Figure 7a. An edge about a triangular or other polygonal opening would serve the purpose.

80 85 The ball end rests in this inverted conical portion of the bore, or upon the edge 63' being centered by gravity in either event. The support in the bracket and the ball end of the ferrule together form a ball and socket suspension of the tube adapting it to hang 90 vertically in the can.

90 So as not to require too large an opening I also preferably chamfer the lower end of the bore at 64 in both forms, thereby increasing the freedom of lateral motion of the tube with respect to its bracket. The thimble is provided with a thawing needle guide or cap 65 and with a drain 66.

95 100 A stop collar 67, mounted upon the tube somewhat below the bracket loosely locks the tube and bracket together while the screw connection between the ferrule thimble and the tube makes it easy to separate the bracket and tube if special conditions should ever make this desirable.

105 110 In Figures 9, 10 and 11 I have shown a few among the various other forms of thimble and collar and tube connection by which loose connection is made between the tube and bracket while giving proper self-centering support for the tube. In each of these forms it will be seen that the thimble, tube and collar form a unit securing the desired support from the bracket.

115 120 In all three figures the thimbles, 61', 61² and 61³ form supports for the collar 67', 67² and 67³ respectively. In Figure 9 the tube is supported directly from the thimble while in Figures 10 and 11 the tube is threaded into the thimble-support collar.

125 130 The air tube is shown provided with the usual small air holes 68, spaced above the bottom of the tube. These holes admit air into the water even after the bottom of the tube has frozen shut.

It will be obvious that the conditions of use do not require that the passage in or through the bracket have continuous walls, though I prefer to have the passage in the form of an aperture with continuous walls thereabout, and have so illustrated it.

In view of my invention and disclosure, variations and modifications to meet undivided whim or particular need will doubtless 10 become evident to others skilled in the art and I claim all such in so far as they fall within the reasonable spirit and scope of my invention.

Having thus described my invention, what 15 I claim as new and desire to secure by Letters Patent is:

1. In an ice plant, a bracket having a passage flared at its upper end, a ferrule seated in said flare, an air tube supported by the 20 ferrule, capable of oscillatory movement to swing the ferrule in the flare and a lock collar below the bracket and preventing removal of the tube through the bracket.

2. In an ice plant, a bracket having a passage flared at its upper end, a ferrule seated in said flare, an air tube supported by the 25 ferrule, capable of oscillatory movement to swing the ferrule in the flare and a lock collar below the bracket and preventing removal of the tube through the bracket, one of the parts, the ferrule or collar being removable.

3. In ice making apparatus, a bracket adapted to engage the rim of an ice can and 30 having a passage therein, in combination with an air tube passing downwardly through the passage, and a support for the air tube about the upper end of the tube forming a universal joint with the wall of 40 the passage.

4. In an ice plant, a unit comprising a bracket adapted to hook loosely over the rim of an ice can and having an opening, a drop air tube passing through the opening, 45 a support for the tube resting upon the surface about the opening, and a stop, rigid with respect to the tube, permanently secured beneath the opening and preventing upward removal of the tube from the bracket.

5. In an ice plant, an ice can having a longitudinal stiffening bead, a unit comprising 50 a bracket recessed to fit the bead and centering the tube and adapted to hook over the rim of the can and a drop air tube depending from the bracket over the center of the can, adapting the tube to hang vertically when supported by the bracket.

6. In an ice plant, a bracket having a passage, an air drop tube having its upper end 55 loosely passing through the passage and a support for the tube mounted upon the upper end of the tube above the bracket and having ball-end loose bearing with the bracket permitting swinging movement of the tube.

7. In an ice plant, a bracket having a pas-

sage conically chamfered on its upper side, an air drop tube having its upper end loosely passing through the passage and a support for the tube mounted upon the upper end of the tube above the passage and having a ball-end loose bearing with the chamfer of the bore permitting swinging movement of the tube.

8. In an ice plant, a bracket having a passage, an air drop tube having its upper end loosely passing through the passage, a support for the tube mounted upon the upper end of the tube above the passage, forming a unit with the tube and resting loosely upon the bracket about the passage to permit swinging movement of the tube, and a collar larger than the passage mounted upon the unit below the smallest section of the bore of the passage.

9. In an ice plant, a bracket having a passage, an air drop tube having its upper end loosely passing through the passage, a support for the tube mounted upon the upper end of the tube above the passage, resting loosely upon the bracket about the passage and having ball end bearing with the bracket to permit swinging movement of the tube, and a collar larger than the passage mounted upon the tube below and near to the bore of the passage.

10. In a device of the character stated, a brine receiving tank, a freezing can, a member arranged upon the can top and provided with a socket, a ball-like member having an aperture therethrough seated in said socket, an agitator tube penetrating the said aperture, and means for securing said tube to said member.

11. In a device of the character stated, a brine receiving tank, a freezing can, a horizontally disposed member arranged upon the can top and provided with a depending socket, a ball-like member having an aperture therethrough seated in said socket, an apertured agitator tube penetrating the said aperture, and means adjacent the tube top for securing said tube to said member.

12. In a device of the character stated, a member adapted for support upon a freezing can, said member being provided with a socket, and an air tube having its upper end secured to a ball-end bearing positioned within said socket, said ball-end bearing having an opening therethrough.

13. In an ice plant, the combination of an ice can, a bracket adapted to be supported thereon and having a passage therethrough an air drop tube adapted to be positioned in said ice can and having its upper end loosely passing through the passage and a support for the tube mounted upon the upper end of the tube above the bracket and having ball-end bearing with the bracket.

14. In an ice plant, the combination of an

ice can, a bracket adapted to be supported thereon and having a passage therethrough and the walls of the latter shaped to form a semi-spherical seat for a ball, a ball positioned on said seat, and a perforated air tube secured to said ball, and depending therefrom within said can, said ball and air tube being adapted to be lifted vertically upwardly from said seat.
